TRANSMISSION SHIFT CONTROL MODULE FOR MOBILE OR STATIONARY EQUIPMENT

Peter D. Adams, La Canada, and Warner R. Lauper, San
Pedro, Calif.; said Lauper assignor to Quadrastat Con-
trols Corporation

Filed Apr. 19, 1974, Ser. No. 462,230

Term of patent 14 years

Int. Cl. D15—01

U.S. Cl. D55—1 G

FIG. 1.

FIG. 2.

FIG. 3.

FIG. 4.

FIG. 5.

FIG. 1 is a top plan view of a transmission shift control module for mobile or stationary equipment, showing our new design;

FIG. 2 is a bottom plan view thereof;

FIG. 3 is an end elevational view thereof, the opposite end being a mirror image of the end shown herein;

FIG. 4 is a side elevational view thereof as seen from the left in FIG. 1; and

FIG. 5 is a side elevational view thereof, as seen from the right in FIG. 1.

We claim:

The ornamental design for a transmission shift control module for mobile or stationary equipment, as shown.
